(57) **CLAIM**

The ornamental design for a two piece snap-fit cap or glide, as shown and described.

DESCRIPTION

FIG. 1 is a perspective view showing the two piece snap-fit cap or glide according to the present invention in an assembled condition;

FIG. 2 is a top plan view thereof;

FIG. 3 is a front side elevational view thereof;

FIG. 4 is a right side elevational view thereof;

FIG. 5 is a rear side elevational view thereof;

FIG. 6 is a left side elevational view thereof;

FIG. 7 is a bottom plan view thereof; and,

FIG. 8 is an exploded perspective view of the two piece snap-fit cap or glide in an unassembled condition.
